UNITED STATES PATENT OFFICE.

JACOB CLOSS, OF ST. ANSGAR, IOWA.

COMBINED AIR REGULATOR AND DEFLECTOR.

1,841,494.

Specification of Letters Patent. Patented May 25, 1920.

Application filed August 23, 1919. Serial No. 319,390.

To all whom it may concern:

Be it known that I, JACOB CLOSS, a citizen of the United States, residing at St. Ansgar, in the county of Mitchell and State of Iowa, 5 have invented certain new and useful Improvements in Combined Air Regulators and Deflectors, of which the following is a specification.

The invention relates to an attachment for 10 use in cooking stoves, and more particularly to the class of combined air regulators and deflectors for oil burning wick stoves.

The primary object of the invention is the provision of a device or attachment of this 15 character, wherein the same when placed within the stove relative to the air intake about the burner regulates the inflow of air and deflects the same from a direct course about the flame when the burner is lighted 20 for increasing the combustion and to spread said flame for assuring maximum heating qualities with a minimum consumption of oil, the combustion being improved when the flame is low or high and without resultant 25 smoking thereof.

Another object of the invention is the provision of a device or attachment of this character, wherein a maximum fullness of flame is assured and the heat therefrom materially 30 increased both in intensity and volume, the burner being maintained cool below the flame issuing therefrom to avoid overheating of said burner and the air admitted about such burner is deflected from a direct draft 35 upon the flame to avoid the contracting of the latter and thereby procuring the best results in the use of the stove.

A further object of the invention is the provision of a device or attachment of this 40 character, wherein the air admitted to the combustion chamber about the burner in the stove is regulated and controlled for supplying the requisite quantity of air and directing the inflow of the same for improving the 45 combustion during the use of the stove to assure maximum heat and elimination of smoke and odor.

A still further object of the invention is the provision of a device or attachment of 50 this character, wherein it is readily applied about the burner within an oil stove and can be removed when the occasion requires to permit the cleaning thereof or said stove, the device being of novel construction to regulate and deflect the air in a proper course

within the combustion chamber for a more perfect combustion.

A still further object of the invention is the provision of a device of this character, which is extremely simple in construction, 60 thoroughly reliable and efficient in its purpose, and inexpensive to manufacture and install.

With this and other objects in view, the invention consists in the features of construction, combination, and arrangement of parts as will be hereinafter fully described, illustrated in the accompanying drawing and pointed out in the claims hereunto appended.

It is to be understood, of course, that 70 changes, variations and modifications may be made in the invention, such as come properly in the scope of the appended claims, without departing from the spirit of the invention, or sacrificing any of its advantages.

In the accompanying drawing, Figure 1 is the fragmentary side elevation of a wick burner and chimney, for oil cooking stove, showing the collar for supporting the chimney upon the burner, with the device constructed in accordance with the invention applied, the chimney being partly broken away and supporting collar being in section.

Fig. 2 is a perspective view of the device removed from the chimney.

Fig. 3 is a fragmentary perspective sectional view of the chimney showing a portion of the device in position therein.

Fig. 4 is a fragmentary vertical sectional view showing a modified form of the device.

Fig. 5 is a view similar to Fig. 3, showing a further modified form of the invention.

Similar reference characters indicate corresponding parts throughout the several views in the drawing.

Referring to the drawing in detail, A designates a portion of a wick burner which is of any approved form and B a portion of a chimney of a construction ordinarily used in oil burning wick cook stoves. Located 100 within the burner A is the usual oil wick C above which is arranged a flame spreader D which may be of any ordinary well known construction.

The burner A has formed exteriorly thereon an annular bead constituting a shoulder 105 for the mounting of a collar 11 thereabout to support the chimney B which at its lower end is formed with a suitable central opening for telescopically receiving therein the 110

collar 11 which projects upwardly into the chimney to properly position the burner therein. The collar 11 is of slightly greater diameter than the external diameter of the 5 burner A and has formed internally thereof suitable brackets or rests 12, engageable with the bead or shoulder 10, on the burner, the brackets or rests 12 being radially disposed to sustain the collar spaced concentrically 10 relative to the burner A and for the supporting of said collar upon the same.

The chimney B at its end engaged with the collar 11 is formed with a circular rim 13 constituting a bottom shaped to provide 15 an annular trough 14 having at its inner periphery an upstanding vertical flange 15 for frictional engagement with the collar 11, the rim 13 being formed at intervals with air inlet openings or apertures 16, which may 20 be of any desirable size to admit air about the burner A interiorly of the chimney B. If found desirable the collar 11 may be provided with suitable apertures or openings 25 17 for augmenting the admission of air into the said chimney.

Adapted to be located within the trough 14 in the bottom 13 of the chimney B is the attachment which comprises a split annular member 18, preferably made from sheet 30 metal, although the same may be made from any other material if found desirable and this member has at its upper edge a series of outturned upperly divergent deflector wings or fingers 19, each being formed with 35 an outwardly tapered free or outer extremity 20 whereby the wings or fingers adjacent each other of the series present therebetween substantially V shaped gaps 21 serving as air spaces or ways, concentrically of said member, it being understood, of course, that the formation of the extremities 20 can be varied 40 to increase or decrease the gaps 21. Furthermore the shape of the wings or fingers 19 can be varied so as to increase or decrease 45 the spaced relation thereof in the outward divergent disposition of said wings or fingers. The member 18 at the end 22 has one of the wings or fingers, 19, partly removed 50 to provide a stop nib 22, the latter to coact 55 with the adjacent or underlying wing or finger 19 at the other end of said member 18 to preserve the circular formation of the member 18 when placed within the trough 14 and to hold the ends of said member in registering overlapped relation to each other.

The wing or finger 19 next to the stop nib 22 is curved to provide a latch 23 for engagement with the body of the chimney B 60 at the juncture of the bottom 13 therewith so as to hold the device properly seated within the trough 14 when placed therein and to avoid any possibility of displacement thereof in the trough.

65 In applying the device the same is intro-

duced centrally through the bottom 13 of the chimney B when removed from the burner and is worked into position to engage in and become seated within the trough 14 so that the member 18 will encircle the vertical 70 flange 15 concentrically thereof and contact therewith, while the wings or fingers 19 will be disposed in their series in upperly divergent relation circumferentially about the collar 11 to lie above the air inlet openings or 75 apertures 16 in the bottom 13 of the chimney for action upon the air entering the openings or apertures 16 to deflect said air in the direction of the outside wall of the chimney B, the air being regulated in its course from 80 the trough 14 upwardly through the gaps 21 and between the wings or fingers 19 for circulation within the combustion chamber formed by the chimney B to effect an improved combustion and the spreading of the 85 flame with resultant issuance of maximum heat and a minimum consumption of fuel.

The device with the wings or fingers 19 when placed within the bottom of the chimney B serves as a combined air regulator and 90 deflector for the air flowing through the openings or apertures 16 in the bottom of the chimney B to the point of combustion of the fuel and thereby properly direct the air into the combustion chamber for effecting a materially stronger indirect draft up 95 through the chimney with a resultant more perfect combustion, and increase of heat with a minimum consumption of fuel and at the same time eliminating smoke and odor 100 issuing from the chimney.

It is clearly apparent that by the use of the device, a quicker heat transit is assured and a proper current of cool air is maintained about the burner below the point of 105 the flame for the cooling of said burner to prevent the overheating thereof. Furthermore the air is properly deflected into the combustion chamber in the chimney B to avoid direct draft therein for an improved combustion and a heat increase without any increase in the consumption of oil when the stove is in use.

In Fig. 4 of the drawing there is shown 115 a slight modification of the invention wherein in the bottom 24 of the chimney 25 for the cooking stove has its vertical wall 26 formed with the device, the wings or fingers 27 being integral with the vertical flange 26 and are constructed and arranged correspondingly to the wings or fingers 19 hereinbefore described for regulating and deflecting air admitted through the air inlet openings or 120 apertures 20 in the bottom 24 of the chimney.

In Fig. 5 of the drawing there is shown 125 a further modification of the invention wherein the device is in the form of a convoluted or coiled annular member 29, preferably made from a single length of wire, the convolutions or coils 30 being arranged 130

in properly spaced relation to each other and the ends of the wire are formed with interfitted links 31 for connecting said ends together to provide the annular member 29.

- 5 The member 29 is adapted to be fitted within the trough 32 in the bottom 33 of the chimney 34 as is clearly shown in Fig. 5 of the drawing. The convolutions or coils 30 of the member 29 overlie the air inlet openings 10 or apertures 35 in the bottom 33 of the chimney 34 to act upon the air for regulating the same and deflecting the course thereof to the combustion chamber in the chimney 34 for the admission of the air concentrically 15 about the flame and adjacent the outside wall of the chimney and this member 29 operates in a manner similar to the other forms of the device hereinbefore described.

It will be apparent that by reason of the 20 annular shape of the member 29 the coils or convolutions 30 thereof are spread apart a greater distance at the outer periphery of the same than at its inner periphery so that a greater amount of air passes between 25 the coils or convolutions at the outer circumference of the member than at the inner periphery, thus causing the air to flow with greater volume upwardly next to the body of the chimney 24 for action upon the flame 30 to spread the same and this course of the air has a tendency to improve the combustion in the chimney and to intensify the heat of the flame when the burner is lighted.

From the foregoing it is thought that the construction and manner of operation of 35 the invention will be clearly understood, and therefore, a more extended explanation has been omitted.

What is claimed is:

1. The combination with an oil burning 40 cook stove having a burner and a chimney, the same provided with air inlet openings, of an attachment comprising a deflector in the chimney above the air openings for retarding the direct course of air admitted 45 through the openings and deflecting said air into said chimney toward its side wall concentrically of the burner.

2. An attachment of the character described comprising a circular member 50 adapted to be disposed over the air inlet openings in the chimney of a cooking oil stove and having portions arranged relative to each other for effecting the changing of the air course through said openings and 55 directing said air adjacent to the side wall of the chimney.

3. An attachment of the character described comprising a split circular member and series of radially disposed upwardly 60 divergent wings on said member and having tapered free extremities providing air gaps therebetween.

In testimony whereof I affix my signature hereto.

JACOB CLOSS.
